UNITED STATES PATENT OFFICE.

FRANK C. SANFORD, OF BRIDGEPORT, CONNECTICUT.

VICE.

1,279,011.

Specification of Letters Patent. Patented Sept. 17, 1918.

Application filed March 15, 1918. Serial No. 222,661.

To all whom it may concern:

Be it known that I, FRANK C. SANFORD, a citizen of the United States, residing at the city of Bridgeport, county of Fairfield, State 5 of Connecticut, have invented certain new and useful Improvements in Vises; and I do declare the following to be a full, clear, and exact description of the invention, such as will enable others skilled in the art to which 10 it appertains to make and use the same.

This invention relates to certain new and useful improvements in a vise, and it has for its principal object to provide a screw adjustable jaw embodying in its mounting 15 auxiliary means for effecting a final and quick adjustment of the jaw toward and from the work subsequent to the setting of the jaw by its screw adjustment.

Further the invention resides in the features of construction and the arrangements and combinations of parts hereinafter described and claimed, reference being had to the accompanying drawings wherein—

Figure 1 is a top plan view of a vise constructed in accordance with the present invention;

Fig. 2 is a side elevation thereof;

Fig. 3 is a longitudinal section on line 3—3 of Fig. 1;

Fig. 4 is a transverse section on line 4—4 of Fig. 1;

Fig. 5 is a perspective view of a slide bearing; and

Fig. 6 is a bottom plan view of the eccentric end of the cam lever.

Referring more in detail to the drawings, the numeral 1 designates the base formed with a longitudinal chamber or groove 2 and side flanges 3. A fixed jaw 4 is arranged at one end of the base for co-operation with the movable jaw 5 which is slidably connected to the base by detachable plates 6 that engage beneath the flanges 3 and constitute therewith a dovetail connection, as depicted in Fig. 4. In a rear extension of the adjustable jaw is formed a transverse guideway 7 in the bottom of which is a slot 8 registering with and extending lengthwise of the chamber 2 but crosswise of 50 the guide 7.

Disposed longitudinally within the chamber 2 and journaled at each end thereof in the base 1 is a rotatable shaft 9 having screw threads 10 on that portion within the cham-

ber for engagement by and for advancing 55 and retracting a sleeve nut 11. The outer end of the screw shaft 9 is extended through the end of the base and is equipped with a hand wheel 12 by which the shaft may readily be turned and the nut advanced in either 60 direction. The extension of screw shaft 9 is journaled in a bushing 22 which is threaded in the outer end of the base 1 and held against accidental or unauthorized unscrewing by a small screw 23 that extends within 65 a hole 24 in said bushing. This bushing will thus withstand the thrust of shaft 9 in an efficient manner, and when the screw 23 is removed the bushing may be unscrewed and the shaft withdrawn. A stub shaft 13 is 70 formed on the nut 11 and extends upwardly through the slot 8 to constitute a support for the eccentric or cam 14 through which it passes off center. Slidably mounted in the guideway 7 is a slide bearing 15 which 75 has a round opening 16 formed in it to receive the hub-like eccentric 14, the latter having an overhanging flange 17 to engage over the slide bearing and keep it seated in the guideway. A nut 18 and washer 19 engaged over the upper threaded end of the stub shaft serves to maintain the parts in 80 their operative relation.

In operation, the base may have a swivel mounting or be firmly bolted down on a 85 work bench or table by passing the fasteners through the ears 20. The work being then placed against the fixed jaw, hand wheel 12 is turned to rotate the screw shaft and advance the nut 11 to obtain the desired adjustment of the movable jaw. Now, by swinging the cam lever 21, formed on the eccentric 14, backwardly, the latter will give the movable jaw the final tightening movement to securely and firmly grip the 90 work. To release the work it is only essential to swing the lever in either direction toward the jaws, such swinging action turning the eccentric in the slide bearing to both slide the latter in its guideway and also 100 shift it to effect adjustment of the movable jaw from whatever position it has been given by the screw adjustment. After once being set by the screw shaft the cam adjustment will be the only one required 105 to be operated while working on a like stock of work. Thus, a quick adjustment is provided for clamping and unclamping the

work. This is especially desirable in a vise where the primary adjustment is of the screw type.

What is claimed is:—

- 5 1. A vise comprising a base having a fixed
jaw at one end and formed in its upper face
with an elongated chamber, a screw shaft
journalized in the base at each end of the
chamber and disposed lengthwise within the
latter, an adjustable jaw slidably connected
10 to the base for movement toward and away
from the fixed jaw and provided with a
transverse guideway having a crosswise slot
registering with the chamber, a nut mount-
15 ed within the chamber on the threads of the
shaft for being moved by rotating the lat-
ter, a stub shaft carried by the nut and ex-
tending through the slot of the movable jaw,
a cam lever journalized on the stub shaft and
20 provided with an eccentric, a slide bear-
ing slidable in the transverse guideway and
formed with an opening to receive the ec-
centric, and means for securing the slide
bearing in its guideway and the eccentric to
25 the stub shaft.

2. A vise comprising a base having a fixed
jaw at one end and formed in its upper face
with an elongated chamber, a screw shaft
journalized in the base at each end of the
30 chamber and disposed lengthwise within the
latter, an adjustable jaw slidably connected
to the base for movement toward and away
from the fixed jaw and provided with a
transverse guideway having a crosswise slot
35 registering with the chamber, a nut mount-
ed within the chamber on the threads of the
shaft for being moved by rotating the lat-
ter, a stub shaft carried by the nut and ex-
tending through the slot of the movable jaw,
40 a cam lever journalized on the stub shaft and
provided with an eccentric, and means slid-
able in the transverse guideway and formed
with an opening to receive the eccentric.

4. In a vise, a base having an elongated
chamber, a threaded shaft journalized in the
base lengthwise of the chamber, a nut
mounted on the shaft for advancement
within the chamber when the shaft is ro-
50 tated, an adjustable jaw slidable on the base
and formed with a transverse guideway and
a slot extending crosswise of the guideway
and lengthwise of the chamber, a stub shaft
carried by the nut and extending upwardly
55 through the crosswise slot and into the trans-
verse guideway of the jaw, a shiftable bear-
ing plate slidable in the transverse guideway
and formed with a round opening through
which the stub shaft projects, a cam lever
60 journalized on the stub shaft and provided
with an eccentric fitting the round opening
of the shiftable bearing plate to exert a lat-
eral pressure thereagainst and move the jaw,
and an outwardly extending flange on the
65 cam lever for engaging the bearing plate
to hold the latter in the transverse guide-
way.

5. In testimony whereof I affix my signature
in presence of two witnesses.

FRANK C. SANFORD.

chamber, a threaded shaft journaled in the base lengthwise of the chamber, a stub shaft threaded at its outer end and having its inner end integrally connected to a nut, said nut being mounted on the shaft for advancement within the chamber when the shaft is rotated, an adjustable jaw slidable on the base over its chamber and formed with a slot extending lengthwise of the latter to receive the upwardly projecting stub shaft, a cam lever journaled on the stub shaft and provided with an eccentric for shifting the jaw, and a nut secured on the upper threaded end of the stub to hold the cam lever thereon.

4. In a vise, a base having an elongated chamber, a threaded shaft journaled in the base lengthwise of the chamber, a nut mounted on the shaft for advancement within the chamber when the shaft is rotated, an adjustable jaw slideable on the base and formed with a transverse guideway and a slot extending crosswise of the guideway and lengthwise of the chamber, a stub shaft carried by the nut and extending upwardly through the crosswise slot and into the transverse guideway of the jaw, a shiftable bearing plate slideable in the transverse guideway and formed with a round opening through which the stub shaft projects, a cam lever journaled on the stub shaft and provided with an eccentric fitting the round opening of the shiftable bearing plate to exert a lateral pressure thereagainst and move the jaw, and an outwardly extending flange on the cam lever for engaging the bearing plate to hold the latter in the transverse guideway. 60 65 70 75 80

In testimony whereof I affix my signature
in presence of two witnesses.

FRANK C. SANFORD.
